A TERRITORY FOR

UNITED STATES PATENT OFFICE.

ALBERT E. HALL, OF OAKLAND, CALIFORNIA, ASSIGNOR TO HALL FURNACE CO., INC.,
OF OAKLAND, CALIFORNIA, A CORPORATION OF CALIFORNIA.

GAS-FURNACE.

1,099,876.

Specification of Letters Patent. Patented June 9, 1914.

Application filed May 19, 1913. Serial No. 768,479.

To all whom it may concern:

Be it known that I, ALBERT E. HALL, a citizen of the United States, residing at Oakland, in the county of Alameda and State of California, have invented new and useful Improvements in Gas-Furnaces, of which the following is a specification.

This invention relates to air heaters and particularly to a gas furnace.

10 It is one of the objects of the present invention to provide a gas furnace in which the maximum heating efficiency of the heat units produced by the combustion of the fuel may be had; to provide an improved 15 gas furnace in combination with a register supported by the structural elements of the building to be heated; and to provide in a gas furnace novel means for igniting the burner of the furnace from a position adja-

20 cent to the register, thus avoiding the necessity of the person desiring to light the burner leaving the room in which the register may be arranged or into which the heat from the furnace may be delivered.

25 It is a further object of the invention to provide a furnace structure which can be very readily attached to and detached from the building structure with a minimum cost and without requiring expensive alterations 30 or changes in the structure, and also to provide in combination with an air heater means through which the burner may be seen, and thus more readily and carefully controlled to produce the desired flame.

35 The invention consists of the parts and the construction and combination of parts as hereinafter more fully described and claimed, having reference to the accompanying drawing, in which the figure is a central vertical section through the furnace.

40 This invention comprises a furnace or air heating structure consisting of three substantially concentric drums, as an outermost flue or casing 2, an intermediate wall 3, and an innermost drum 4, the latter being closed with a top 5 and a bottom 6 and these members being interconnected by air tubes 7 extending parallel through the heat drum 4. The heat drum 4 and the intermediate wall 50 3 terminate in approximately a common plane and these are rigidly connected with the casing or shell 2 by a grill or other suit-

able frame or brace 8, provided with openings of ample area for the flow of air, as will be hereinafter set forth.

55 Mounted upon the top 5 of the heat drum 4 is a window 9 of suitable area, and which may be of mica or other heat-resisting transparent material, through which, when looking downward, there is rendered visible a 60 burner 10. The burner 10 is here shown as mounted within a burner chamber 11 attached to the bottom 6 of the heat drum 4; the burner chamber 11 projecting downwardly through an aperture 12 of slightly 65 larger area than the area of the burner chamber and which is formed in a bottom 13 closing the lower portion of the furnace casing or shell 2 except for the aperture 12 through which the burner chamber 11 projects.

70 An important feature of the present invention consists in the means for connecting the furnace with the structural elements of the building in which it may be mounted, 75 and which means also form flues for the conveyance of cold air to the air chamber, within the intermediate wall 3 of the furnace, and for conveying the heated air therefrom into the room or apartment to be 80 heated. To that end the shell 2 of the furnace is shown as tapered at its upper portion and continued in the reduced neck 14 which terminates adjacent to and rests in a floor register 15 of any suitable type, which 85 may be mounted upon the floor 16 of the structure. To the joints 17 of the floor are attached suspending hangers 18 appropriately and detachably secured to the casing 2 of the furnace, and which hangers 90 substantially support the entire load of the furnace by direct connection with the floor joists 17.

95 The hot air flue 3 is contracted and extended upwardly at a throat 19, concentric with the neck 14, and also seats in the lower portion of the register 15 which is provided with the usual apertures, through the outermost, as 20, of which the cold lower strata of air can flow downwardly in a space between the neck 14 and throat 19, while through the inner apertures 21 of the register the heated air will rise from over the heat drum. Thus a constant circulation is 100

created and maintained by the downward flow of air in the space between the furnace walls 2 and 3 and into the space above the furnace bottom 12 and below the heat drum bottom 6, from which space the air will rise through the several air tubes 7 and pass into the throat 19, issuing in a heated state through the register apertures 21, whence it freely rises.

10 A particular advantage of the present furnace is that all of the heat units, except the small proportion escaping with the burnt gases at the escape flue 4^a, which is located in the drum 4 well down toward its bottom, 15 are conserved and utilized by heating the upwardly rising volume of air in the annular chamber or flue between the walls 3 and 4. The downward draft of air from the register apertures 20 and in the space between the outermost wall 2 and the hot air flue 3 prevents the loss of heat units from the wall 3 of the hot air flue, since the downwardly moving colder volume of air will become heated by the heat radiating from the 20 wall 3 and its temperature again increased as it flows upwardly through the hot air chamber between the wall 3 and the drum 4.

Another important advantage of this construction is that the hot and warm members 30 of the furnace are insulated from contact with any of the structural elements, particularly where the throat 19 of the hot air flue 3 passes through the floor joists and connects with the register 15, since the throat 19 35 is surrounded by a volume of cold air moving downwardly within the neck 14.

It is a further object of this invention to eliminate the necessity of the attendant or person desiring to ignite fuel at the burner, 40 or to manipulate the control valves thereof, having to go from one floor, or from one room, to another of the building, for the simple purpose of regulating the valves of the burner. To that end I have provided a novel 45 means for igniting the gas conveyed to the burner 10 by a supply pipe 22. The igniting means consists of a tube 23 supported and opening at its upper end in the register 15; the tube being projected downwardly 50 through the furnace and through one of the air tubes 7 of the heat drum, through the bottom 13 of the furnace, and terminating with an open end just above a burner 24 having burner openings directed upwardly and horizontally. The burner discharges in close proximity to the open end 55 of the air tube 23 and the horizontal burner openings discharge a jet of gas toward an aperture 24' formed in the burner chamber 60 11 just above the burner 10.

The two-way jet burner 24 is provided with gas by a suitable connection 26 with the supply pipe 22, in which pipe 26 is mounted an adjustable control valve 27 hav-

ing a stem 28 projecting upwardly through 65 the furnace and terminating and resting in the register 15. Into the upper end of the valve stem 28 may be applied a suitable key whereby it may be turned to open or close 70 the valve 27 to permit the passage of gas 70 through a reducing valve 29.

When it is desired to ignite the gas at the burner 10, the operator or person present turns the valve stem 28 to admit gas to the valve 29, through which it flows in a reduced 75 quantity to the two-way jet burner 24. Then by applying a light, match or flame from any source at the top of the igniter tube 23 the gas rising from the jet burner 24 therein will be ignited and will backfire, causing combustion to occur at the 80 double tips of the burner 24. The horizontal jet projects through the aperture 24' of the burner chamber 11 and this may be observed by the person looking through 85 the apertures of the register 15 and the window 9 of the heater drum, through which the burner 10 in the chamber 11 will be visible. When the pilot flame is projecting into the burner chamber 11, the 90 operator then places a key over the upper end of a valve stem 30 in the register 15, which stem projects downwardly and connects with a main valve 31 controlling the 95 flow of gas from the feed pipe 22 to the burner 10, thereby opening the valve 31 to admit gas to the burner, whereupon it will be ignited by the pilot jet at the aperture 24 of the burner chamber, and, as before stated, by observing the burner through the 100 window 9 from above the register 15 the size of the flame at the burner can be nicely determined by manipulating the valve 31 to admit the necessary quantity of gas. The operator then re-adjusts the key upon the 105 upper end of the pilot valve stem 28 and turns off the pilot flame.

Having thus described my invention, what I claim and desire to secure by Letters Patent is—

1. A floor hot air heater comprising a register, an outer and an intermediate shell secured to and depending from the register, an inner drum having a top and bottom which top and bottom are spaced from the 115 ends of the outer shell, air tubes extending through the top and bottom of the inner drum, said top having a window therein which is in vertical alinement with said register, a burner chamber alined with the window and register and connected to the bottom of said inner drum and projecting below the bottom of the outer shell, a bottom for the outer shell having an aperture through which the lower end of the burner 120 chamber projects, a burner arranged below the bottom of said outer shell and projected into said chamber, a supply pipe for the 125

burner, a rotatable valve on said pipe, and a vertical rod connected to the valve and rotatably connected to the register.

2. A floor hot air heater comprising a register, an outer and an intermediate shell secured to and depending from the register, an inner drum having a top and bottom which top and bottom are spaced from the ends of the outer shell, air tubes extending through the top and bottom of the inner drum, said top having a window therein which is in vertical alinement with said register, a burner chamber alined with the window and register and connected to the bottom of said inner drum and projecting below the bottom of the outer shell, a bottom for the outer shell having an aperture through which the lower end of the burner chamber projects, and a burner below the bottom of the outer shell and projected into said chamber.

3. A floor heater composed of a register, a shell secured to and depending from said register and having a bottom, a burner chamber connecting with the shell interior, a supply pipe for the burner, a pipe communicating with the supply pipe, a two-way jet burner connected to the second mentioned pipe, a vertical air pipe having its upper end secured to the register and having its lower end arranged over one of said jets, the

other of said jets registering with a lateral aperture provided therefor in the burner chamber, a rotatable valve in each of said pipes, and a rod for each valve, said rods being connected at their lower ends to the valves and having their upper ends rotatably secured to the register.

4. A floor heater consisting of a register, an outer and an intermediate shell secured to and depending from the register, an inner shell having a top and a bottom, the bottom of the inner shell and the bottom of the intermediate shell terminating in a common plane which is located above the plane of the bottom of the outer shell, a grill connected to the outer and intermediate shells and to the lower end of the inner shell for supporting the latter, a burner chamber connected to the bottom of the inner shell and depending below the lower end of the outer shell, a burner in the chamber, and a bottom for the outer shell through which said chamber projects.

In testimony whereof I have hereunto set my hand in the presence of two subscribing witnesses.

ALBERT E. HALL.
